DESIGN FOR A PERMANENT WAVE MACHINE

Edward Jacobsen, New York, N. Y., assignor to
Eugene, Ltd., New York, N. Y., a corporation of
New York

Application December 31, 1936, Serial No. 66,835

Term of patent 14 years

To all whom it may concern:

Be it known that I, Edward Jacobsen, a citizen
of the United States and resident of New York,
county and State of New York, have invented a
new, original, and ornamental Design for Per-
manent Wave Machines, of which the following
is a specification, reference being had to the ac-
companying drawing, forming a part thereof.

Fig. 1 is a perspective view of a permanent wave

machine embodying my design and showing the
rear and one side of said machine; and

Fig. 2 is a perspective view of the machine
shown in Fig. 1, showing the front and other side
thereof.

I claim:

The ornamental design for a permanent wave
machine, substantially as shown.

EDWARD JACOBSEN.
